UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-DELIVERY MECHANISM FOR PRINTING-MACHINES.

1,205,590.

Specification of Letters Patent. Patented Nov. 21, 1916.

Application filed December 28, 1914. Serial No. 879,324.

To all whom it may concern:

Be it known that I, HOWARD M. BARBER, a citizen of the United States, and a resident of Stonington, in the county of New London and State of Connecticut, have invented a new and useful Improvement in Sheet-Delivery Mechanism for Printing-Machines, of which the following is a specification.

The object of this invention is to provide novel means for delivering sheets flat in either one or a plurality of piles, the sheets when delivered in a plurality of piles being arranged side by side.

My invention includes means for feeding a web at a certain speed and means for delivering the sheets cut therefrom, at a higher speed; intermediate variable speed means being employed for taking the advance edge of the web at the speed of the web and transferring the sheets cut from the web, at a higher speed, as for instance, the speed of the sheet delivery device.

My invention also includes means for slitting the sheets longitudinally of their travel after they have been cut from the web, and means for insuring the feeding of the sheets to the slitting mechanism and the taking of the sheets by the slitting mechanism absolutely square with the side edges of the sheets so that the sheets will be accurately slit.

A practical embodiment of the invention is represented in the accompanying drawings, in which,

Fig. 1 represents in side elevation so much of a sheet delivery mechanism for printing machines as includes my invention. Fig. 2 is a section taken from front to rear just inside of the near side frame, and Fig. 3 is a diagrammatic section taken from front to rear centrally through the delivery mechanism.

A pair of rotary cutters 1, 2 are mounted on suitable shafts 3, 4, and are herein shown as having one set of coacting blades 5, 6, for cutting a sheet transversely from the web every revolution of the cutters. Guides 7, 8, for the web are located below the cutters 1, 2.

The sheet delivery table is denoted by 9. A sheet delivery device is arranged to deposit the sheets on the table 9, which delivery device is herein shown as an endless delivery carrier 10 having sets of grippers 11 thereon at suitable intervals. A slitting cylinder 12

is mounted upon a shaft 13 driven at a continuous speed, which cylinder is herein shown as provided with two sets of grippers 14, 15. A transfer cylinder 16 is mounted on a shaft 17, which cylinder is provided with a set of grippers 18 arranged to transfer the sheets from the slitting cylinder 12 to the delivery device 10. A variable speed cylinder 19 is mounted on a shaft 20, and it is provided in the present instance, with two sets of grippers 21, 22, arranged to take the advance edge of the web and transfer the sheets cut therefrom to the grippers 14 and 15 respectively of the slitting cylinder 12.

The sheets are slit longitudinally of their travel on the cylinder 12 into any number of sections by providing a slitting shaft 23, with one or more slitting disks 24, coacting with the slitting cylinder 12.

Suitable cam mechanisms are provided for insuring the opening and closing of the several sets of grippers at the proper times for the transfer of the sheets, which cam mechanisms will not be specifically described herein as they may be of well known or approved construction.

The web is fed through the rotary cutters 1, 2, at a certain speed. The slitting cylinder 12 is driven at a higher surface speed, in the present instance through a train of gears 25, 26, 27, 28, 29. The endless sheet delivery carrier 10 and the transfer cylinder 16 are driven at the same surface speed as the slitting cylinder 12, through a train of gears 29, 30, 31, 32, 33. The cylinder 19 is driven at a variable surface speed ranging from the slower speed of the web to the higher surface speed of the slitting cylinder 12, through the variable speed gears 34, 35, which gears are so arranged that the grippers 21 and 22 will be traveling at the speed of the web at the time for grasping the advance edge of the web and will be traveling at the increased speed of the grippers 14 and 15 respectively of the slitting cylinders at the time the sheets cut from the web are transferred thereto.

As the longitudinal cut in the sheet is made after the sheets have been cut from the web, it is essential that the sheets be taken by the slitting cylinder perfectly square with the side edges of the sheets. This is accomplished by the device hereinabove described, by means of which the ad-

vance edge of the slower traveling web is taken at the speed of the web and the sheets cut therefrom are transferred to the slitting mechanism at the speed of the slitting mechanism.

5 Where I have used the term "cylinders," I wish to include any type of carrier for the sheets, and where I have referred to the term "grippers", I wish to include any suitable 10 means for engaging the sheets to lead them through the prescribed paths.

It is evident that various changes may be resorted to in the construction, form and 15 arrangement of the various parts without departing from the spirit and scope of my invention, and hence I do not wish to limit myself to the structure herein set forth, but

What I claim is:

1. In a machine of the character described, 20 means for feeding a web at a certain speed, means for cutting sheets therefrom, sheet delivery means including a constant speed rotary sheet carrier and an endless sheet delivery carrier both traveling at a higher 25 surface speed than the web, and a variable speed rotary carrier having grippers arranged to take the advance edge of the web at the speed thereof and to transfer the sheets cut from the web to the constant rotary carrier at the surface speed thereof.

2. In a machine of the character described, 30 means for feeding a web at a certain speed, means for cutting sheets therefrom, sheet slitting means traveling at a higher surface speed than the web and means arranged to take the advance edge of the web at the speed thereof and transfer the sheets cut from the web to the slitting means at the speed thereof.

40 3. In a machine of the character described, means for feeding a web at a certain speed, means for cutting sheets therefrom, sheet slitting means traveling at a higher surface speed than the web, means arranged to take 45 the advance edge of the web at the speed thereof and transfer the sheets cut from the web to the slitting means at the speed thereof, and an endless sheet delivery carrier traveling at the surface speed of the slitting means.

4. In a machine of the character described, 55 means for feeding a web at a certain speed, means for cutting sheets therefrom, rotary sheet slitting means traveling at a higher surface speed than the web and rotary means arranged to take the advance edge of the web at the speed thereof and transfer the sheets cut from the web to the slitting means at the surface speed thereof.

60 5. In a machine of the character described, 65 means for feeding a web at a certain speed, means for cutting sheets therefrom, rotary sheet slitting means traveling at a higher surface speed than the web, rotary means arranged to take the advance edge of the

web at the speed thereof and transfer the sheets cut from the web to the slitting means at the surface speed thereof, and an endless sheet delivery carrier traveling at the surface speed of the said rotary slitting means.

6. In a machine of the character described, means for feeding a web at a certain speed, means for cutting sheets therefrom, a sheet slitting means including a constant speed sheet slitting carrier having a higher surface speed than the web, and a variable speed rotary carrier having grippers arranged to take the advance edge of the web at the speed thereof and to transfer the sheets cut from the web to the sheet slitting carrier at the surface speed thereof.

7. In a machine of the character described, means for feeding a web at a certain speed, means for cutting sheets therefrom, a sheet slitting means including a constant speed sheet slitting carrier having a higher surface speed than the web and a variable speed rotary carrier having grippers arranged to take the advance edge of the web at the speed thereof and to transfer the sheets cut from the web to the sheet slitting carrier at the surface speed thereof, and an endless sheet delivery carrier traveling at the surface speed of the sheet slitting carrier.

8. In a machine of the character described, means for feeding a web at a certain speed, means for cutting sheets therefrom, a carrier having a higher surface speed than the web, means for slitting the sheets longitudinally of their travel thereon and means arranged to take the advance edge of the web at the speed thereof and transfer the sheets cut from the web to the slitting carrier at the surface speed thereof.

9. In a machine of the character described, means for feeding a web at a certain speed, means for cutting sheets therefrom, a carrier having a higher speed than the web, means for slitting the sheets longitudinally of their travel thereon, means arranged to take the advance edge of the web at the speed thereof and transfer the sheets cut from the web to the slitting carrier at the surface speed thereof and an endless sheet delivery carrier traveling at the surface speed of the sheet slitting carrier.

10. In a machine of the character described, means for feeding a web at a certain speed, means for cutting sheets therefrom, a rotary carrier having a higher surface speed than the web, means for slitting the sheets longitudinally of their travel thereon, and a variable speed rotary carrier having grippers arranged to take the advance edge of the web at the speed thereof and to transfer the sheets cut from the web to the slitting carrier at the surface speed thereof.

11. In a machine of the character de-

- scribed, means for feeding a web at a certain speed, means for cutting sheets therefrom, a rotary carrier having a higher surface speed than the web, means for slitting the sheets longitudinally of their travel thereon, a variable speed rotary carrier having grippers arranged to take the advance edge of the web at the speed thereof and to transfer the sheets cut from the web to the slitting carrier at the surface speed thereof, and an endless sheet delivery carrier traveling at the surface speed of the sheet slitting carrier.
12. In a machine of the character described, means for cutting sheets from a traveling web, means traveling at a greater surface speed than the web for slitting the sheets longitudinally of their travel and means traveling at a varying surface speed for taking the sheets at the speed of the web and transferring them to the slitting means at the surface speed thereof.
13. In a machine of the character described, means for cutting sheets from a traveling web, means traveling at a greater surface speed than the web for slitting the
- 15 sheets longitudinally of their travel, means traveling at a varying surface speed for taking the sheets at the speed of the web and transferring them to the slitting means at the surface speed thereof, and means for delivering the slit sheets.
- 16 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470
